Primary Examiner — Manpreet Matharu*Assistant Examiner* — Keith Wilson(74) *Attorney, Agent, or Firm* — Price Heneveld LLP(57) **CLAIM**

The ornamental design for the seating shell, as shown.

DESCRIPTION

FIG. 1 is a top perspective view of a seating shell embodying the present invention;

FIG. 2 is a front perspective view of the seating shell;

FIG. 3 is a rear elevational view of the seating shell;

FIG. 4 is a rear perspective view of the seating shell;

FIG. 5 is a front elevational view of the seating shell;

FIG. 6 is a side elevational view of the seating shell;

FIG. 7 is a top plan view of the seating shell; and,

FIG. 8 is a bottom plan view of the seating shell.

The broken lines included in the drawings represent environment only and form no part of the claimed design.
